US00D696253S

(12) **United States Design Patent**
Akana et al.

(10) **Patent No.:** US D696,253 S
(45) **Date of Patent:** ** Dec. 24, 2013

(54) **PORTABLE DISPLAY DEVICE WITH CASE**

(75) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **14 Years**

(21) Appl. No.: **29/415,145**

(22) Filed: **Mar. 7, 2012**

Related U.S. Application Data

(57) **CLAIM**

The ornamental design for a portable display device with case, as shown and described.

DESCRIPTION

FIG. 1 is a top front perspective view of a portable display device with case, showing the case in an open position, showing our new design;

FIG. 2 is a bottom rear perspective view thereof;

FIG. 3 is a front view thereof;

FIG. 4 is a rear view thereof;

FIG. 5 is a bottom view thereof;

FIG. 6 is a top view thereof;

FIG. 7 is an enlarged left side view thereof;

FIG. 8 is an enlarged right side view thereof;

FIG. 9 is a front view thereof showing the case in a closed position;

FIG. 10 is an enlarged bottom view in two parts;

FIG. 11 is an enlarged top view in two parts;

FIG. 12 is a cross-sectional view of the portable display device with case, with the case shown in an open position;

FIG. 13 is a cross-sectional view of the portable display device with case, with the case shown in a closed position;

FIG. 14 is a cross-sectional view of the portable display device with a portion of the case; and,

FIG. 15 is an enlarged cross-sectional view of a portion of FIG. 14.

The broken lines in the Figures show portions of the portable display device with case which form no part of the claimed design.

The shade lines in the Figures show contour and not surface ornamentation. The hatched lines in the Figures show portions of the case which form no part of the claimed design.
